CLAIM

The ornamental design for a hat as shown and described.

DESCRIPTION

FIG. 1 is a front view of a design for a hat according to the present invention.

FIG. 2 is a left side view of the hat.

FIG. 3 is a right side view of the hat.

FIG. 4 is a back view of the hat.

FIG. 5 is a top view of the hat; and,

FIG. 6 is an interior view of the hat.

The evenly spaced long broken lines depict portions of the hat that form no part of the claimed design. The evenly spaced short broken lines depict features of the hat that form no part of the claimed design. The dash-dot-dash broken lines depict stitching that forms no part of the claimed design.

1 Claim, 6 Drawing Sheets
